UNITED STATES PATENT OFFICE.

FLETCHER V. WALSH AND COLVIN M. REED, OF SAN FRANCISCO, CALIFORNIA.

PRINTING-PLATE FOR COLORED PHOTO-ENGRAVING AND THE PROCESS FOR PRODUCING THE SAME.

1,157,197.

Specification of Letters Patent.

Patented Oct. 19, 1915.

Application filed September 1, 1914. Serial No. 860,112.

To all whom it may concern:

Be it known that we, FLETCHER V. WALSH and COLVIN M. REED, citizens of the United States, residing in the city and county of San Francisco and State of California, have invented new and useful Printing-Plates for Colored Photo-Engraving and the Process for Producing the Same, of which the following is a specification.

0 The invention relates to printing plates for colored photo-engraving and the process of producing the same and has especial reference to the shifting of the screen through which the subject is projected onto the exposed negative, and it consists of the printing plates and the improved method of shifting the screen so that the resulting dots on one plate or color record will always bear the same relative position to the dots on 20 all of the other plates.

One of the most important characteristics of the process for producing colored photo-engraved printing plates is that the dots on the said plates shall bear the same relative 25 position to each other on the finished printed picture in order to reproduce a uniform graduation of shades and tints without producing what is known as a "moiré antique" result, or pattern.

30 Printing plates constructed in accordance with our present invention comprise a series of plates wherein the dots printed from one plate will overlap the dots printed from a second or third plate in a uniform degree 35 throughout the printing surface.

The features of the invention are first, to produce a series of different screen negatives from one screen that will print a record of each color in dots that uniformly 40 overlap the dots of the other plates; second, to provide means whereby the pattern or "moiré antique" result of the present process will be eliminated; third, to provide means whereby a greater number of plates 45 or color records may be used to the end that a greater number of colors may be printed and uniformly blended together, thereby resulting in a finer and more artistic reproduction.

0 The accompanying drawings, which form a part hereof, represent the invention in its preferred form.

Figure 1 is a vertical longitudinal sec-

tional view of a photo-engraving camera disclosing the screen in position, the negative 55 behind the screen, and the movable lens slidably mounted upon the front of the camera the dotted, and the dot and dash lines indicating the first and second positions of the projected subject. Fig. 2 is a 60 front elevation of the front end of the camera disclosing the lens slidably mounted therein and the means whereby the said lens is shifted. Fig. 3 is a sectional view taken 65 on line X—X of Fig. 2 of the drawings. Fig. 4 is a front elevation of a screen, the upper half of which discloses the result when the screen has been shifted in accordance with the present invention disclosing the absolute lack of the "moiré antique" 70 result or pattern. Fig. 5 is a greatly enlarged diagrammatic view of the dots resulting from the present invention wherein is shown the manner in which the dots of one plate, 75 shown in full lines, are uniformly overlapped by the dots, indicated in dotted lines, of a second plate. Fig. 6 is a front elevation of an ordinary screen, wherein for purposes of better illustration, the lines are disclosed as running in one direction only instead of 80 crossing each other at right angles. Fig. 7 is a view of two screens wherein the lines run at angles to each other as in the present state of the art thereby producing the pattern or "moiré antique" result. 85

In order that a clear understanding of the present invention may be had it is necessary to describe the process used in the present state of the art, which is as follows: In the present state of the art printing plates are 90 produced by photographing the subject onto a negative. It is only possible to approximate to the printing of a flat or graduated tone, such as appears in photography, by producing a broken or granulated surface 95 which shall present a series of lines or dots that, when inked and impressed upon paper, shall by the variations of proximity and size give the impression of an unbroken tone. This granulated or broken surface is produced by photographing through a screen consisting of two sheets of glass, each sheet having lines ruled diagonally thereon, and at mathematically equal distances from each other. The sheets of glass are sealed together with the diagonally ruled lines cross- 100 105

ing each other at right angles, the result being a grating or screen containing innumerable little squares of clear glass through which the light can pass, which it can not do through the ruled lines which are filled with an opaque pigment.

To produce a half-tone block a negative is exposed in the camera in the usual way, with a screen quite close to it but not in contact; and the subject is photographed onto the negative through the screen, and what is termed a "screen negative" is the result. It is a photograph of so much of the subject as could effect the negative through the little clear squares of the screen, and represent the tones of it by innumerable little dots, the size and proximity of which are regulated by the fineness or coarseness of the screen used.

20 In reproducing a colored picture a negative or record of each separate color is obtained by photographing the subject through a separate filter. Each filter will absorb and refuse passage to certain colored rays, while 25 permitting the passage of others. For instance, a filter of a certain color will absorb and stop the passage of red and green rays, while permitting the passage through it of a violet or blue. When a colored subject is 30 placed before the camera, with one of these filters between it and the exposed negative, the rays of light of the color which can pass through the filter to the negative will be the only ones which can affect it. In this manner 35 it is possible to obtain, on separate negatives and by means of separate filters, one for each negative, a record of each primary color of the subject. These records are not colored photographs but negatives which 40 may be translated into color by the use of colored inks. The principle governing the process is analysis or separation followed by recombination. When printing plates made from these separate negatives are inked and 45 printed one over the other they combine again the colors which were separated by the filtering process and give approximately a reproduction of the original subject in its true colors. In printing with these separate 50 plates, it is evident that were the same screen used in their production the lines or dots would print on top of one another; but a great deal of the color results depends upon a considerable portion of each color 55 being on the white paper. Consequently it is necessary to turn the screen at a different angle for each block, so that the lines should not fall on each other but should cross each other. Instead of turning the screen, a different 60 screen is used for each different color wherein the lines on each screen for each color lie at an angle to all of the other screens used for all of the other colors.

The crossing of the screen lines will produce in the finished product what is known

as the moiré antique result, and the greater the number of color records or plates used, the more pronounced is this effect. The present invention entirely eliminates the moiré antique result, thereby allowing a 70 greater number of color records, and consequently, a more artistic and faithful reproduction of the original subject. The present invention also provides a means whereby a number of color records or plates may be 75 produced through the same screen without turning the lines thereon, or the screen itself.

Instead of using different screens having the lines thereon at different angles for each 80 separate plate, if the same screen is used but shifted on a line parallel with one set of lines on the said screen each time a separate negative is exposed, it is evident that when the negatives are developed and the printing 85 plates made therefrom inked and impressed upon a sheet of paper that the dots printed from one plate will overlap the dots printed from the other plates in proportion to the amount that the screen was shifted. In 90 other words, instead of changing the relative positions of the dots for each plate by turning the screen a more uniform relation of the dots is obtained by shifting the screen on a line parallel with the lines thereon, 95 which will give the effect disclosed in the upper half of Fig. 4 and in Fig. 5 of the drawings, said upper half of Fig. 4 having been shifted in the direction indicated by the inclined arrow.

As it is not deemed practical to shift the screen we have provided means for producing the same result which consists in shifting the lens on the camera which is accomplished in the following manner.

Referring to the drawings the numeral 1 is used to designate a photo-engraving camera of the usual type and 2 is a plate holder mounted within the back thereof. The negative 3 to be exposed is placed within the 110 plate holder 2 and back of the screen 4. The subject 5 is projected through the lens 6, in the front end of the camera 1, and the screen 4 onto the negative 3.

The lens 6 is mounted upon a plate 7 115 which is slidably mounted within the guides 8 secured to the front 12 of the camera 1. The plate 7 is provided with a lug 9 arranged to engage the threaded portion 10 of a stem 11 rotatably mounted within a standard 15 secured to the front 12 of the camera 1. The stem 11 is provided with a suitable knob 14 having suitable graduations thereon by means of which the amount of rotation of the knob 14 and stem 11 may be indicated.

The central or normal position of the lens 6 is indicated by means of a mark 17 on one edge of the plate 7 which registers with a similar mark 18 on the adjacent edge of the 130

guide 8 on that side of the said plate 7. The registration of the mark 17 with the mark 18 is facilitated by means of a small magnifying glass 19 mounted upon the guide 8 5 and directly over the said mark 18.

In producing the successive negatives, one for each color, the first negative is placed in the camera 1 and exposed in the usual manner, through the proper filter, not shown, 10 for the color to be registered. The first negative is then removed and a second negative, and appropriate filter, is placed in position. Instead of moving the screen 4 in a line parallel with one set of lines on the 15 said screen, the image is slightly shifted by turning the knob 14 the desired amount which will shift the plate 7 and the lens 6 therein. The second negative is then exposed, through an appropriate filter. Each 20 time a successive negative is exposed the lens 6 is shifted so that the resulting dots will each lie in a different position on each different negative.

While the lens 6 is shifted before each successive negative is exposed so that the dots on any two plates will not register, it must be understood that the said dots on one plate will always bear the same relative position to the dots on every other plate in the 30 series.

In Fig. 5 of the drawings we have illustrated the relative positions of the dots resulting from one plate or negative to the dots resulting from another plate or negative.

It is obvious from the foregoing that we have provided an improved series of plates for color printing and an improved process for producing the same wherein more artistic 40 results may be obtained, a greater number of colors and color plates may be used, and where only one screen is necessary for the production of the said plates. It is also obvious that the direction of inclination, or 45 the angle at which the projection or lens is shifted is immaterial if the lens or projection is shifted in a line parallel with one set of lines on the screen. It is also evident that the lens may be stationary and the 50 screen shifted on a line parallel with one set

of lines on the said screen with the same results.

Having thus described our invention what we claim as new and desire to secure by Letters Patent is—

55

1. Printing plates for a colored photo-engraving process comprising a series of half-tone plates whereon the lines running in one direction and formed of dots or lines on one plate will register with similar lines 60 on the other plates, and the lines running at right angles to the first mentioned lines and likewise formed of dots or lines will overlap and lie parallel to lines running in the same direction on every other plate of 65 the series.

2. The process of producing color printing plates which consists of projecting the subject onto the exposed negatives through a screen and of shifting the projection on 70 each successive negative exposed so that the resulting dots or lines on one plate will uniformly overlap the dots or lines on every other plate.

3. The process of producing color printing plates which consists of projecting the subject onto the exposed negatives through a screen and of shifting the projection on each successive negative exposed an equal amount so that the resulting dots or lines on 75 one plate will uniformly overlap the dots or lines on every other plate.

4. The process of producing color printing plates which consists of projecting the subject onto the exposed negatives through a screen and of shifting the projection on each successive negative exposed an equal amount on a line parallel with one set of lines on the screen so that the resulting dots or lines on one plate will uniformly overlap 80 the dots and lines on every other plate.

In witness whereof we hereunto set our signatures in the presence of two subscribing witnesses.
